UNITED STATES PATENT OFFICE

WILLIAM GOWIE, OF CANTON, OHIO, ASSIGNOR TO THE HARVARD COMPANY, OF CANTON, OHIO, A CORPORATION OF OHIO

AUXILIARY FOOT REST.

Application filed September 10, 1929. Serial No. 391,614.

The invention relates to auxiliary foot bars 11 and 11' secured at their upper ends to the seat 12 and extending downwardly and forwardly therefrom to the apexes 13 and 13' from which the outer beam portions 14 and 14' extend horizontally forward and are pivotally connected at their outer ends with an angularly adjustable adult's foot rest extension 15.

10 The objects of the present improvements include the provision in a dental chair of an auxiliary folding child's step or platform and foot rest, conveniently combined with an adult's step or platform and foot rest, the auxiliary step or platform and foot rest being adapted to be extended and automatically unfolded into operative position and withdrawn and automatically folded into inoperative unobtrusive position, by an easy foot or manual operation.

These objects are attained in the present improvements as will hereinafter be set forth in detail and claimed.

25 A preferred embodiment of the improvements is illustrated in the accompanying drawings forming part hereof, in which

Figure 1 is a fragmentary plan view of a dental chair illustrating the adult's foot rest in operative position, and the auxiliary foot rest after being automatically unfolded into operative position;

Fig. 2, a fragmentary side elevation thereof, dot and dash lines indicating intermediate positions of the several parts of the auxiliary foot rest during a withdrawing and folding movement;

Fig. 3, a view similar to Fig. 2, illustrating the auxiliary foot rest completely withdrawn and folded into inoperative and unobtrusive position; and

40 Fig. 4, a fragmentary side elevation of the opposite side of the dental chair from that shown in Fig. 2, showing the auxiliary foot rest extended, parts being broken away to show the operating mechanism.

Similar numerals refer to similar parts throughout the several views.

45 The dental chair indicated generally at 10 is provided with a foot rest frame comprising the laterally spaced angled foot rest side

55 The side bar beam portions 14 and 14' support a stationary adult's foot rest platform 16, and the side bars above the apexes 13 and 13' are pivotally connected as by screws 17 and 17' respectively, with an auxiliary foot rest platform member 18, preferably adjacent the inner laterally extending side edge thereof.

60 The auxiliary platform 18 preferably adjacent its lateral edge forward of the pivot screws 17 is pivotally connected as by stub shafts 19 and 19' with an auxiliary foot rest extension 20, and the platform 18 is provided beyond the stub shaft 19 with a stop 21 for supporting the extension 20 in the position illustrated in Figs. 1 and 2 when in use.

65 Improved operating means indicated generally at 22, are provided for automatically rotating the auxiliary foot rest platform member 18 about its pivot screws, from its inoperative and non-obtrusive position illustrated in Fig. 3, to its operative position illustrated in Figs. 2 and 4, and the reverse, and for simultaneously folding and unfolding the extension 20 by rotating the extension, which is preferably secured on the stub shafts 19 and 19', in the stub shaft bearings preferably formed in the platform 18.

70 The operating means indicated generally at 22, may include a crank arm 22' secured on the shaft 19' and extending therefrom in the direction of the platform extension 20.

75 The outer end of the crank arm 22' is pivotally connected as by means of a pin 23 with one end of an angle link 24; and the link 24 extends from the pivot pin 23 alongside of the platform 18 and about the pivot screw 17' where the other end of the link is connected preferably by a slot and pin connection indicated at 25 with the side bar 11', the slot and pin connection being located below the pivot screw 17'.

The slot and pin connection preferably may include a slot 26 formed in the angle link 24, and a pin 27 extending through the slot and secured in the side member 11'.

5 In the illustrated embodiment of the invention, a web 28 extends between the chair side bars 11 and 11', which necessitates providing the slot and pin connection 25 in order to obtain clearance of the link 24 when the 10 platform is folded out of use into the non-obstructive position illustrated in Fig. 3.

Otherwise the slot and pin connection may be any desired type of pivotal connection; and the platform 18, the crank arm 22', the 15 link 24, and the side arm 11' between the pivot screw 17' and the pin 27, comprise a four-bar linkage, the members of which are proportioned to impart the desired folding and unfolding movements to the platform 20 extension 20 during rotation of the platform 18.

For rotating the platform 18, and for limiting the outward swinging thereof, a stop arm 29 extends from the platform at the 25 side of the link 24 and from the axis of the pivot screws 17, 17' in the opposite direction to the direction of extension of the platform.

The upper surface of the stop arm is arranged to abut against a stop 30 which may 30 be secured on the side bar 11, and the auxiliary foot rest may be actuated by a combined crank handle and pedal 31 having the knurled foot engaging portion 31', and which extends laterally and outwardly from the 35 stop arm 29.

When the auxiliary foot rest is in the extended position shown in Figs. 2 and 4, a downward force applied on pedal 31 rotates the platform 18 about the pivots 17 and 17', 40 an intermediate position of the platform being shown in dot-dash lines in Fig. 2. As aforesaid, the platform 18 constitutes one member of the four bar linkage for folding the extension 20. As the platform is rotated, 45 the link 24, another member of the linkage, is rotating about pivot 27. Since side arm 11', which constitutes a third member of the linkage, is stationary and both pivots 17 and 27 are fixedly mounted thereon, when platform 50 18 rotates, the position of the outer end of link 24 pivoted at 23 on extension 20 changes relative to pivot 17, because the distance between points 23 and 27 remains the same. Crank arm 22', the fourth member of the 55 linkage, connects pivots 19 and 23. Thus, as platform 18 rotates about pivots 17 and 17', and link 24 about pivot 27, crank arm 22' will rotate extension 20 about pivot 19 to the folded position shown in Fig. 3.

60 When the auxiliary foot rest is in the folded position indicated at 22, a force applied on the pedal 31 in the downward and rearward direction, rotates the platform 18 about the pivots 17 and 17' to the position 65 indicated in full lines in Fig. 2, and the afore-

said four-bar linkage operates to unfold the extension 20 and rotate the same in its stub shaft bearings to the extended position illustrated in Fig. 2.

Accordingly, by the present improvements 70 an auxiliary foot rest is provided for the dental chair 10 as aforesaid, which includes the platform 18 and the extension 20, and which may be automatically folded up and 75 swung back between the side bars, leaving the adult's foot rest unobstructed and ready for use, as illustrated in Fig. 3, or which may be automatically swung outwardly and unfolded and used as a foot rest for a child or 80 a small person, as illustrated in Fig. 2.

I claim:—

1. In a dental chair and the like including a seat and a foot rest frame having spaced side bars and a web extending therebetween, 85 a foot rest including a platform member pivotally mounted between the side bars below said web and adapted to be rotatively drawn within the foot rest frame against the web, an extension pivotally mounted on the platform member for rotating toward and away 90 from the platform member, and an angle link pivotally connected at one end to the extension and extending alongside the platform and around the pivotal mounting of the platform and having a slot and pin connection at its other end with the frame for simultaneously rotatively folding the extension upon the platform member when the latter is rotatively withdrawn within the foot rest frame and for simultaneously rotatively extending the extension relative to the platform member when the latter is extended.

2. In a dental chair and the like including a seat and a foot rest frame having spaced side bars and a web extending therebetween, 95 a foot rest including a platform member pivotally mounted between the side bars below said web and adapted to be rotatively drawn within the foot rest frame against the web, an extension pivotally mounted on the platform member for rotating toward and away 100 from the platform member, and means connecting the extension and the frame for simultaneously rotatively folding the extension upon the platform member when the latter is rotatively withdrawn within the foot rest frame and for simultaneously rotatively extending the extension relative to the platform member when the latter is extended, the connecting means including a crank arm secured 105 to the extension and a link pivotally connected at one end with the arm and extending alongside the platform and around the pivotal mounting of the platform and having 110 a slot and pin connection at its other end with the frame.

In testimony that I claim the above, I have hereunto subscribed my name.

WILLIAM GOWIE.
